UNITED STATES PATENT OFFICE.

DAVID GESTETNER, OF LONDON, ENGLAND, ASSIGNOR TO D. GESTETNER, LIMITED, OF LONDON, ENGLAND.

DUPLICATING MACHINE.

Application filed October 18, 1924. Serial No. 744,380.

To all whom it may concern:

Be it known that I, DAVID GESTETNER, a subject of the King of Great Britain and Ireland, and residing at Neo-Cyclostyle 5 Works, Tottenham Hale, London, N. 17, England, have invented certain new and useful Improvements in and Relating to Duplicating Machines, of which the following is a specification.

10 This invention relates to duplicating machines, that is to say device by which reproductions of manuscript or typewritten matter, drawings and the like are produced with the aid of stencils, and has for its object to 15 provide improvements therein.

The object of the invention is to provide an improved duplicating machine of the kind in which two stencil carriers are associated with means whereby stencils secured 20 to each of said carriers are caused to operate simultaneously and on opposite sides of a sheet of impression-receiving material.

A duplicator in accordance with the invention comprises in addition to inking cylinders over which a stencil secured to an endless flexible carrier is caused to travel for producing a stencil impression on one side of a sheet of impression-receiving material an endless flexible carrier for a second stencil adapted simultaneously to produce a stencil impression on the reverse side of the said sheet, said second stencil carrier being associated with inking cylinders in a similar manner to the carrier for the first-mentioned 35 stencil.

As when the machine is fed with individual sheets from a pile thereof during the interval between the forming of stencil impressions on one sheet and the production of 40 impressions on the succeeding sheet the pressure roller must be withdrawn from the adjacent inking cylinder in the machines of known construction so a machine in accordance with the present invention comprises 45 also means whereby the inking cylinder associated with one stencil carrier may be retracted from the adjacent cylinder associated with the second stencil carrier if it is intended for use in producing stencil impressions on individual sheets.

Such means may in general resemble the 50 means for imparting similar motion to the pressure roller in duplicating machines provided with a flexible carrier for a single 55 stencil.

Thus, for instance, the inking cylinder associated with the carrier for the stencil operating on the lower surface of the sheet of impression-receiving material may be actuated by means similar to that employed for 60 imparting similar motion to the pressure roller of existing machines to cause the said cylinder to approach and recede from the adjacent inking cylinder associated with the carrier for the stencil operating to produce 65 a stencil impression on the upper surface of the sheet of impression-receiving material.

The cylinder associated with the carrier for one of the stencils may be arranged in a frame with which an ink-distributing roller 70 or waver roller is also associated, secured as by pivots to the main frame of the machine or the support therefor so that it may be rocked about its pivots to cause one of the inking cylinders to be brought toward and 75 retracted from the adjacent inking cylinder associated with the other stencil carrier.

Alternatively, the frame carrying the inking cylinders with which one of the stencil carriers is associated may be arranged to be 80 moved as a whole in any other way in order to move the inking cylinder co-operating with one stencil carrier toward and away from the adjacent inking cylinder of the other stencil carrier. 85

To facilitate the desired motion of the inking cylinders in the direction indicated springs, counterpoises or the like may be provided.

When, on the other hand, the machine is 90 designed for use in producing stencil impressions on a band or a "continuous" roll of material there is no need to arrange for the periodic motion of the lower pair of inking cylinders or one of them toward and away 95 from the lower inking cylinder of the upper pair; consequently the mechanism adapted to secure this result may be omitted from a machine intended for such use or may be arranged to be rendered inoperative. 100

In order that a machine in accordance with the invention may be employed when desired for producing a stencil impression on one side of a sheet or band of impression-receiving material a flexible member adapted 105 to be arranged to travel over the inking cylinders and constitute a cushioned support for the sheet of material may be employed.

Alternatively, means may be provided whereby the inking cylinder associated with 110

one of the stencil carriers may when desired, be permanently spaced apart from the adjacent inking cylinder associated with the other stencil and a pressure roller brought 5 into position to operate in conjunction with the last-mentioned cylinder.

One construction of a duplicator in accordance with the invention is illustrated in side elevation, partly in section, in the accompanying drawing, in which:—

1 represents the frame of the machine, 2 and 2^a the inking cylinders, 3 the flexible band connecting these two cylinders over which one of the stencils associated with its 15 flexible carrier travels. With these cylinders, as is usual, an ink-distributing roller 4 is associated.

The lower of the two inking cylinders is driven by a pinion 5 from the spur wheel 6 mounted on the spindle 7 on which also a sprocket 8 is mounted. The chain 9 connects this sprocket with the sprocket 10 mounted on the spindle 11 on which also a spur wheel 12 and a cam 13 are mounted.

25 The spur wheel meshes with a second spur wheel 14 which is in engagement with the spur wheel 15. These two spur wheels being of the same diameter operate to rotate the inking cylinders 16 and 16^a with which 30 flexible bands 17 and a flexible stencil carrier are associated in the usual manner, a waver roller 18 being also provided for distributing the ink over the surface of the inking cylinders. These two cylinders and 35 their associated waver roller are mounted in bearings 19 and 19^a in the frame 20 which is connected to one arm of the bell-crank lever 21 which is mounted on the pivot 22 on the main frame of the machine.

40 The other arm of this bell-crank lever is provided with a roller 23 bearing upon the cam referred to above, which operates periodically to raise the frame and move the lower pair of inking cylinders, the flexible carrier and the waver roller associated therewith toward the lower member of the upper pair of inking cylinders at suitable intervals, namely when a sheet of paper is being fed between them, and to permit the lower 45 pair of inking cylinders to be retracted when the fastening means of the upper stencil carrier passes below the lower member of the upper pair of inking cylinders and the like device passes over the upper member of the lower pair of inking cylinders. The feed of the paper is effected in the usual manner, the pile of paper being represented by the reference 24 in the accompanying drawing, by means of the pusher mechanism 25 which is of known character and is driven through the intermediary of the toothed wheels 26 and 27 from the main driving spindle of the machine.

As will be understood, with a device in accordance with the invention the adjacent

cylinders operating in conjunction with the two stencil carriers being simultaneously brought to bear on the impression-receiving surface, each performs the function of a pressure roller in relation to the other while 70 the ink on the cylinders, the stencil carrier and stencil form cushioning or resilient coverings for the cylinders.

Having now described my invention, what I claim as new and desire to secure by Letters Patent is:—

1. A stencil duplicator for use in the reproduction of facsimiles of typewritten, manuscript, printed matter, drawings and the like, comprising a main frame, a plurality of inking cylinders rotatably mounted in said frame, an endless flexible stencil carrier located about said plurality of inking cylinders, means for rotating the cylinders and thereby causing the flexible stencil carrier to travel over the surfaces thereof, a second frame associated with the main frame of the machine, a plurality of inking cylinders rotatably mounted in the second frame, an endless flexible stencil carrier associated with said plurality of cylinders, means for rotating the cylinders and means for moving periodically the second frame to bring one of the cylinders mounted therein toward one of the cylinders mounted in the main frame, whereby pressure may be exerted upon a sheet of material introduced between the stencil carriers.

2. A stencil duplicator for use in the reproduction of facsimiles of typewritten, manuscript, printed matter, drawings and the like, comprising a main frame, inking cylinders rotatably mounted in said frame, an endless flexible stencil carrier adapted to travel over said inking cylinders, a movable frame, inking cylinders rotatably mounted in the movable frame, a flexible stencil carrier adapted to travel over the cylinders in the movable frame and means adapted periodically to move the movable frame to bring an inking cylinder mounted therein into position against an inking cylinder mounted in the main frame to exert pressure upon a sheet of material fed between said cylinders and to move the frame in the reverse direction.

3. A stencil duplicator for use in the reproduction of facsimiles of typewritten, manuscript, printed matter, drawings and the like, comprising a frame, a pair of inking cylinders rotatably mounted therein, flexible bands connecting the two cylinders, a flexible stencil carrier secured to said bands, means on said flexible stencil carrier whereby a flexible stencil may be secured thereto, a cylinder adapted to distribute a pasty ink over said cylinders, means for rotating the inking cylinders and causing the flexible stencil carrier to travel over the surface thereof, a second frame secured

to the main frame, a pair of inking cylinders rotatably mounted in the second frame, flexible bands connecting the said cylinders, a flexible stencil carrier secured to the 5 bands and means operating periodically to raise the second frame and move the pair of inking cylinders mounted therein and the flexible carrier associated therewith towards the lower member of the pair of 10 inking cylinders mounted in the main frame in order to cause stencils secured to the stencil carriers to operate upon a sheet of material fed between them and means for periodically retracting the movable frame 15 with its associated inking cylinders away from the inking cylinders rotatably mounted in the main frame to permit the stencil fastening means of the stencil carrier associated with the cylinders in the fixed frame and the stencil fastening means of 20 the stencil carrier associated with the inking cylinders in the movable frame to pass freely between the upper member of the pair of inking cylinders secured therein and the lower member of the pair of cylinders 25 rotatably mounted in the fixed frame.

In testimony whereof I have signed my name to this specification.

DAVID GESTETNER.
